UNITED STATES PATENT OFFICE.

CALEB H. SWAN, OF WORCESTER, MASSACHUSETTS.

TRIMMING AND BURNISHING MACHINE.

SPECIFICATION forming part of Letters Patent No. 276,925, dated May 1, 1883.

Application filed August 23, 1882. (Model.)

To all whom it may concern:

Be it known that I, CALEB H. SWAN, of the city and county of Worcester, in the Commonwealth of Massachusetts, have invented certain new and useful Improvements in Trimming and Burnishing Machines for Boots and Shoes; and I do hereby declare the following to be a full and clear description of the invention, such as will enable others skilled in the art to make and use the same, reference being had to the accompanying drawings, which form a part of this specification, and to the letters of reference marked thereon.

The object of this invention is to produce a machine with a combination of cutters and a combination of burnishers attached to universal-jointed arms, and so balanced and arranged as to trim the edges, welt, heel, and feather-edge of boots and shoes and burnish the same, combined in one machine. The machine is so constructed that the operator can apply the combination of cutters and combination of burnishers at any angle to any desired part of the fore edge or heel of a revolving boot or shoe confined and adjusted to the end of a revolving spindle, while the face of the boot or shoe revolves in opposite direction to that of the cutters and burnishers, thereby making a friction movement, which is very essential for the production of a clean, smooth cut and a good burnished edge. I attain these objects by the mechanism illustrated in the accompanying drawings, in which—

Figure 1, Sheet 1, is a side view of the machine, Fig. 2, Sheet 1, is a sectional view of one of the universal-jointed arms. Fig. 3, Sheet 2, is a front view of the machine. Fig. 4, Sheet 2, is a sectional view of the burnishers, spring, friction set-screw, handles, and arbor on which they are adjusted. Fig. 5, Sheet 2, is a sectional view of the cutters, guide-spring, handles, and arbor on which they are adjusted. Fig. 6, Sheet 2, is an end view of the heel-cutter. Fig. 7, Sheet 2, is an end view of the edge-cutter, showing the four recesses. Fig. 8, Sheet 2, is a view of the welt-cutter. Fig. 9, Sheet 2, is a view of the feather-edge knife, showing its gage and its four raised sections, on which the cutters are located. Fig. 10, Sheet 2, represents a face view of the guide, gage, and shield combined in one piece, show-

ing the two openings *a a*, whereby it clears itself from dust, and also the raised bearing *n'* around its center for reducing its friction; and Fig. 11, Sheet 2, is a side sectional view of the same, showing the recessed face *n*, outstanding rim *o*, and sleeve *m*.

Similar letters refer to similar parts throughout the several views.

The standard *A* and the two arms *B* and *B'*, arranged at right angles with each other, support standard-bearings *C* and *C'*, to which they are bolted. The standard *A* may be fastened in a platform or a low table.

D denotes a spindle adjusted in bearings *C*, and projecting out parallel with arm *B'*, and on this spindle are adjusted pulley *I* and boot or shoe *E*, which receive motion by means of belt *F'* from pulley *H* on the driving-shaft *F*. The driving-shaft *F* of the machine is adjusted in the bearings *C'*, and on this shaft there are the loose and driving pulleys *G* and *G'* and pulley *H* (which conveys power to the pulley *I* on the spindle *D*) and the reversible yoke *J*, provided with a long slot, *K*. Said yoke is adjusted midway of said slot to swing loosely in the bearings, and a double-grooved wheel, *L*, is adjusted on said driving-shaft to revolve with it in said slot. This double-grooved pulley conveys power by belt *W* in one direction, and by belt *W'* in the other direction, for the purposes hereinafter set forth. Swivel-joint *O* connects rod *P* to one end of the reversible yoke *J*, and swivel-joint *O'* connects rod *P'* at the other end of said yoke. The other end of rod *P* connects with a jointed yoke, *R*, and rod *P'* with jointed yoke *R'*. In these jointed yokes there are double-grooved pulleys *S* and *S'*, which receive power by belts *W* and *W'* from the double-grooved wheel *L*. Connected to these jointed yokes *R* and *R'* by swivel-joints *T* and *T'* are iron rods *U* and *U'*. The other ends of these rods connect the forks *Y* and *Y'* by ball-and-socket joints *V* and *V'*, and in these forks are adjusted the arbors *X* and *X'*. On arbor *X* are adjusted the cutters *N*, guides, and handles *12*, and on arbor *X'* are adjusted the burnishers *N'*, guide, and handles *12'*, and on the end of each of these arbors *X* and *X'* are grooved pulleys *Z* and *Z'*, which revolve in the forks *Y* and *Y'*. Pulley *Z* receives power from double-grooved pulley *S*, located in yoke *R*, by

belt M, and pulley Z' receives power from pulley S', located in yoke R', by means of belt M'; and to keep these belts in their position there are belt-guides, designated by 6, 7, and 8 in one section of the universal jointed arms, and 6' 7' 8' for the other section. By this devised arrangement I have two sets of universal-jointed arms—one at each end of the reversible yoke J—one of which conveys power to the cutters, and the other conveys power to the burnishers, and they are so evenly balanced that they can be readily reversed or exchanged one for the other and brought to the work at any desired angle or point of the fore edge or heel of the revolving boot or shoe adjusted to the aforesaid revolving spindle D, and driven by belt F' or gear from the driving-shaft F of the machine.

The heel and fore-edge cutters have a combination of knives in each.

First, the fore-edge cutter is a combination of three sets of knives, (see Figs. 7, 8, and 9,) namely, the edge-knife, (see Fig. 7,) which trims the outer edge of the sole. It is a cylinder with four slots, b b b, formed in one end, and fifteen (more or less) grooves, c c c, formed in its face at an angle of about forty-five degrees, so that the outer edges form fifteen (more or less) knives, c c c, running in an angle of about forty degrees from end to end across its face, the formation of which produces a smooth, clean, drawing cut. It is located on the arbor at 1. (See Fig. 5.) Next, the welt-knife (see Fig. 8) is a thin circular piece of steel with its inner edge beveled outward, on which are formed more or less teeth, eee, cut on an angle of about forty-five degrees across its periphery, and having their cutting-edges next to the edge-cutter, to which it is attached by screws or otherwise in the holes ffff, the teeth or knives projecting beyond those of the edge-cutter, so as to allow them to trim and throw the chips from the welt. It is located in the combination on the arbor X' at 2. (See Fig. 5.) The next is the feather-edge knife, (see Fig. 9,) which is composed of a cylinder made to fit loosely on the arbor, so as to slide to and fro, having four raised sections on its inner end, which clutch into four corresponding slots, b b b, in the end of the edge-knife cylinder. The knives 3' 3' 3' are formed on the face of the outer ends of the raised sections on an angle, and around the ends is a ring, l, which serves as a gage in trimming the feather-edge. It is located in the combination on the arbor X at 3, (see Fig. 5,) and by means of the spiral spring i and set-screw h in its rim it is made to conform to any thickness of sole that is desired.

Second. The heel-cutters are a combination of two sets of knives. The edge-cutter, (see Fig. 6, which is an end view,) the teeth of which are formed the same as those of the fore-edge cutter, is located on the arbor X at 5, (see Fig. 5,) and the welt-cutter, located at 4, is formed the same as the welt-cutter above described and shown. These

cutters can be formed or made so as to produce any desired form of edges. The guide gage and shield (see Figs. 10 and 11) is a thin piece of circular iron having an outstanding sleeve, m', and the face n' is recessed to allow the projecting rim O, with which it is provided, to cap over the welt-cutter, thereby shielding the upper-leather from injury. It is adjusted loosely on the arbor X (see Fig. 5) at n, so as to roll as a wheel independent of the cutters in the groove between the upper and the sole, thereby serving as a guide and also as a gage. As it regulates the cut of the cutters by keeping them at a uniform distance from the boot or shoe, the outstanding sleeve m' serves to prevent or preserve it from wabbling. The handles 12 12 are of wood, from which project straight pieces of flat iron 13 13, at the ends of which are bearings 14 14 in which the sleeve m' of the before-mentioned guide-gage and shield revolves on the arbor X. (See Fig. 5.) The handles, with the irons, are fastened together by a bolt, 10, and nuts 17 18 19 20, and a screw, 15, in the end of the arbor. On this arbor are adjusted in their order, first the guide gage and shield at n, next the welt-knife 2, next the fore-edge knife 1, next the feather-edge knife 3, next the spiral spring i, next in the bearing, the guide gage and shield n, and next the heel-trimmers 4 and 5. The end of the arbor is adjusted in the fork Y. (See Fig. 5.)

The burnishers are three in number—namely, the fore edge N' is in two cylinders, and the heel N'' one.

First. The fore-edge burnishers are a combination of two cylinders, 21 and 24. (See Fig. 4.) Cylinder 21 has a projecting lip or rim, 22, formed on one end. The other end is inserted in the cup 23 in the end of cylinder 24, which slides to and fro on the arbor X', and it is kept in position by the spiral spring i'' and a key-way, 26, cut in the inner bearing fitted to a corresponding boss or rib, 27, on the arbor. Cylinder 21 burnishes the fore edge of the shoe, and the projecting lip or rim 22 burnishes the welt, and the inner face, 23, of the cup burnishes the feather-edge. By this arrangement it will adapt itself to any thickness of sole.

Second. The heel-burnisher 29 is a cylinder provided with a lip or rim, 30. (See Fig. 4.) Cylinder 29 burnishes the edge, and the lip or rim 30 burnishes the inner edge of the heel. The fore-edge burnishers are heated by a graduating-screw, 31, and the heel by screw 32, inserted in the irons 13', by being in contact with the outer ends of the cylinders while at great speed.

The handles 12' 12' are with irons 13' 13' inserted in them, (see Fig. 4,) on one of which there is a lip or shield, 33, projected down from the nipple-bearing, which prevents the burnisher from coming in contact with the upper-leather, and also serves as a guide in the crease.

Having thus described my invention, what I claim, and desire to secure by Letters Patent, is—

1. The arms B and B', bearings C and C', driving-shaft F, reversible yoke J, wheel L, pulley H, spindle D, pulley I, and belts W W' and F', for the purpose of conveying power to the cutters, burnishers, and boot or shoe E simultaneously, substantially as shown and described, and for the purposes specified.
2. The combination of the arm B', bearing C', and driving-shaft F, the reversible yoke J, provided with slot K, wheel L, belts W and W', swivel-joint O' and O'', rods P and P', yokes R and R', pulleys S and S', swivel-joints T and T', rods U and U', ball-and-socket joints V and V', forks Y and Y', pulleys Z and Z', belts M and M', and arbors X and X', conveying power to the cutters N and burnishers N' simultaneously, with the continuous revolving boot or shoe E on spindle D, substantially as shown and described, for the purpose specified.
3. The combination, with the welt-knife, of the guide gage and shield, provided with sleeve m and rim O, substantially as shown, and for the purposes set forth.

4. In combination with the edge-knives, the feather-edge knife provided with the raised sections g g g g, knives 3' 3' 3' 3', and ring l, substantially as shown and described.

5. In combination with arbor X, the handles 13 13, provided with bearings 14 14, bolt 10, nuts 17 18 19 20, screw 15, and, in their order, the guide gage and shield n, the welt-knife 2, the fore-edge knife 1, the feather-edge knife 3, 35 spiral spring i, set-screw h, guide gage and shield n, and heel-trimmers 4 and 5, substantially as shown and described.

6. In combination with arbor X', provided with boss 27, the handles 13' 13', one of which is provided with a projection, 33, and, in their order, the fore-edge burnisher 21, provided with cup 23 and keyway 26, spiral spring i'', the heel-burnisher 29, provided with lip 30, and the graduating-screws 31 and 32, substantially as 45 shown and described, and for the purposes specified.

CALEB H. SWAN.
